UNITED STATES PATENT OFFICE.

WILLIAM H. PATTERSON, OF CUYAHOGA FALLS, OHIO, ASSIGNOR OF ONE-HALF TO
WILLIAM O'CONNOR, OF CUYAHOGA FALLS, OHIO.

CONCRETE-BLOCK MOLD.

Application filed April 9, 1924, Serial No. 705,243. Renewed June 11, 1925.

To all whom it may concern:

Be it known that I, WILLIAM H. PATTERSON, a citizen of the United States, residing at Cuyahoga Falls, in the county of Cuyahoga and State of Ohio, have invented certain new and useful Improvements in Concrete-Block Molds, of which the following is a specification.

This invention relates to improvements in concrete block molds having for an object to provide a simple and comparatively inexpensive structure which may be easily operated by the average worker.

Another and important object is to provide a structure which will mold blocks having horizontal and vertical webs which upon assembling a set of these blocks provide vertical and horizontal air-ways whereby an absolutely dry structure is obtainable.

20 A further object is to provide a mold of this character in which the ingots are carried by vertical side and end plates which are hinged to the base of the mold and may be swung outwardly to allow removal of a completed block.

Other objects will be in part obvious and in part pointed out hereinafter.

In order that the invention and its mode of operation may be readily understood by persons skilled in the art, I have in the accompanying illustrative drawings, and in the following detailed description based thereon set out one possible embodiment of the same.

35 Fig. 1 is a side elevation of a mold in operation, a portion of one side wall being broken away and the ingots being shown in dotted lines;

Fig. 2 is an end elevation;

40 Fig. 3 is a detail view showing the relation between the base plate, pallet and lower ingot;

Fig. 4 is a perspective view of one of the blocks formed by this mold and

45 Fig. 5 is a vertical longitudinal sectional view of this block.

Having more particular reference to the drawings throughout which similar characters or reference designate similar parts 50 this improved concrete block mold may be stated as comprising a base portion 6, which obviously may be if desired, supported upon a set of legs 7, and provided with a removable base plate 8 which supports the pallet 9 and the members disposing there above. As

illustrated in Figure 2, this base portion 6 removably supports at one side a face plate, 9 which carries a pair of depending dowel pins 10 snugly fitted within sockets 11 carried by said base. This construction permits 60 of changing the face plates and consequently allows for variance of the design of the block face.

On the opposite side is hinged a side plate 12 which obviously has a plain inner face 65 and serves as a means for retaining the concrete which is poured into the mold. Each end plate 13 is hinged to the base as indicated and carries upon its inner face an ingot 14 whose inner face is arranged in parallel 70 relation with respect to the end wall at the midway point, from which point the said face tapers upwardly and outwardly. The upper end portions of these ingots are adapted to snugly engage with an ingot 15 carried 75 by a removable top or cover plate 16, this cover plate being movable vertically by means of a lever 17 or the like. Mid-way the length of the ingot carried by the top plate, a recess or notch 18 is formed and is 80 adapted to co-act with a similar recess or notch 19 formed in a lower ingot 20 to provide a vertical central transverse web or rib 21 in the block structure. A horizontal web or rib 22 is formed in the block through 85 spacing apart the upper and lower ingots as shown in Figure 1.

As is apparent in Figures 1 and 4 a substantially cross-shaped web or rib connection is provided between the inner and outer 90 faces of each block. These webs being terminated at points spaced inwardly from the ends and upper and lower edges of the block, so as to provide the heretofore mentioned vertical and horizontal air-ways when 95 the blocks are assembled in a structure.

In Figure 3 the manner of supporting the lower ingot 20, is clearly shown and consists of positioning the ingot upon a lower or base plate 8, and then slipping the pallet 23 into 100 position. The side and end walls are then moved upwardly into the position shown in Figures 1 and 2, after which the concrete is poured into the mold. The top plate 16 is then moved into position carrying with it 105 the ingot 15 and through this operation compresses the concrete and forms a solid block. After the concrete has set the top plate is removed, and the side and end plates or 110 walls are swung outwardly and downwardly.

out of engagement with the block. At this point the block may be lifted clear of the entire structure including the lower ingot 20 through moving the pallet 23 vertically.

5 After this operation the original steps may be taken to construct another block.

It is understood that suitable clamps or angle brackets may be employed to secure the side and end walls in position during the 10 block molding process.

Certain changes in the minor details of construction may be resorted to and such changes as fall within the scope of the appended claims I consider within the spirit of 15 my invention.

I claim:

1. A mold of the character described comprising a base a separable vertical face plate arranged at one side of the base, side and 20 end walls hinged to the base, ingots formed upon the inner faces of the end walls, an up-standing ingot removably arranged upon the base and having a central transverse recess, an ingot disposed above the up-standing ingot 25 and having a central transverse recess to

co-act with the first recess to form a vertical web in a block and said ingots being vertically spaced whereby to form a horizontal web in a block.

2. A mold of the character described comprising a base, a pallet arranged upon the base and having a central downwardly diverging opening, an upwardly converging ingot having its lower end seated in said opening, said ingot having a central transverse recess in its upper face, a detachable face plate disposed at one side of the base, side and end walls hinged to the base, ingots carried by the end walls and shaped to snugly engage the upstanding ingot, a top plate, 40 and a depending ingot carried by the top plate and converging downwardly, said depending ingot having a central transverse recess to co-act with the first named recess to form a vertical web in a block, said up-standing and depending ingots being spaced apart to form a horizontal web in a block. 45

In testimony whereof, I affix my signature.

WILLIAM H. PATTERSON.
